Primary Examiner — L. A. Grabenstetter*Assistant Examiner* — Antoinette Martine Suiter(74) *Attorney, Agent, or Firm* — Westbridge IP LLC(57) **CLAIM**

The ornamental design for a distance measuring apparatus, as shown and described.

DESCRIPTION

FIG. 1 is a front perspective view of a distance measuring apparatus showing our new design;

FIG. 2 is a rear perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The broken lines in the drawings illustrate the portions of the distance measuring apparatus which form no part of the claimed design.
